UNITED STATES PATENT OFFICE

JOSEPH J. KECK AND ERNEST E. KELLEY, OF PARSONS, KANSAS

LATERAL ELIMINATOR

Application filed March 10, 1930. Serial No. 434,776.

This invention relates to a lateral eliminator, the present invention being an improvement over that forming the subject matter of an application filed by us on December 26, 1928, Serial No. 328,531, allowed July 29, 1929.

The general object of this invention is to provide the bolts which connect the oil pan with the device with compression springs, to provide a plate to hold the liners in place and to provide the liners with recesses for clearance and otherwise making the previous invention more efficient.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is an elevation, with parts in section, of the invention.

Figure 2 is a view looking toward one end of the device.

Figure 3 is an elevation of the device.

Figure 4 is a section on line 4—4 of Figure 3.

Figure 5 is a bottom plan view with parts broken away.

As shown in these drawings, the axle 1 is formed with an annular central enlargement 2 and a housing or casting 3 is formed with a semi-circular bore in each end part for receiving portions of the axle and with a centrally arranged large chamber 5 of semi-circular shape for receiving a portion of the enlargement 2. The housing is formed with flanges 6 at its ends which are bolted to the boxes 7 so that the housing extends from one

box to the other and is supported by said boxes. A pair of semi-circular liners 8, preferably formed of brass, is placed at the sides of the chamber 5, the chamber being formed with the grooves 9 to receive portions of the liners. These liners fit between the side walls

of the chamber and the sides of the enlargement with a slight clearance, thus forming bearings which prevent shifting or sliding of the boxes on their bearings and hold the locomotive frame in a central position. A very accurate adjustment of the amount of lateral may be had by changing the thickness of the liners. Plates 10 are fastened by screws or the like to the bottom parts of the housing, the corners 11 of the plates forming seats for the ends of the liners, thus holding the liners in position. An annular groove 12 is formed in the outer edge of the inner face of each liner for clearance.

An oil pan 13 encircles the lower part of the enlargement 2 of the shaft, this pan being of semi-circular shape and being fastened to the ends of the enlargement 5 of the housing by the bolts 14 having the compression springs 15 thereon. By yieldingly connecting the oil pan to the housing, there is no danger of the oil pan being jerked off the housing in case a driving box gets stuck to the shoes and wedges and the axle moves downwardly. If this occurred, the oil pan would simply move downwardly with the axle, contracting the springs while the housing or casting remained stationary. Then when the parts were turned to their normal position, the springs would force the oil pan against the bottom of the housing. Semi-circular washers 16 of felt or the like are placed in grooves at the sides of the oil pan and at the sides of the enlargement 5 of the housing to prevent lubricant from running out and these washers also keep dirt from getting into the pan. The liners may be removed and substituted by new ones by removing the oil pan and the plates 10.

The oil pan is provided with an oil hole 17 whereby lubricant or oil can be placed in the pan and an eye bolt 18 is connected with the top of the enlargement 5 of the housing for facilitating the placing of the housing in position or its removal from the axle.

By providing the plates 10 for holding the liners in position, the oil pan can be removed without danger of the liners getting out of place.

It is thought from the foregoing descrip-

tion that the advantages and novel features of the invention will be readily apparent.

It is to be understood that changes may be made in the construction and in the combination and arrangement of the several parts, provided that such changes fall within the scope of the appended claims.

What we claim is:—

1. In combination with an axle and its journal boxes, said axle having a centrally arranged circular enlargement, a housing extending between the boxes and secured at its ends thereto and having a semi-circular chamber therein for receiving a part of the enlargement, liners in the chamber between the enlargement and the side walls of said chamber, plates detachably secured to the under faces of the side parts of the housing and having portions forming seats for the ends of the liners and an oil pan connected with the bottom part of the chamber and enclosing the lower part of the enlargement.
2. In combination with an axle and its journal boxes, said axle having a centrally arranged circular enlargement, a housing extending between the boxes and secured at its ends thereto and having a semi-circular chamber therein for receiving a part of the enlargement, an oil pan, bolts connecting the pan to the under part of the chamber and compression springs on the bolts, said pan enclosing the lower part of the enlargement.
3. In combination with an axle and its journal boxes, said axle having a centrally arranged circular enlargement, a housing extending between the boxes and secured at its ends thereto and having a semi-circular chamber therein for receiving a part of the enlargement, liners in the chamber between the enlargement and the side walls of said chamber, each liner having a recess at the outer edge of its inner face and an oil pan connected with the lower part of the chamber and surrounding the lower part of the enlargement.
4. In combination with an axle and its journal boxes, said axle having a centrally arranged circular enlargement, a housing extending between the boxes and secured at its ends thereto and having a semi-circular chamber therein for receiving a part of the enlargement, liners in the chamber between the enlargement and the side walls of said chamber, each liner having a recess at the outer edge of its inner face, an oil pan connected with the lower part of the chamber and surrounding the lower part of the enlargement and plates placed between the pan and housing and detachably connected with the housing and having parts forming seats for the ends of the plates.

In testimony whereof we affix our signatures.

JOSEPH J. KECK.
ERNEST E. KELLEY.
